UNITED STATES PATENT OFFICE.

PAUL H. BAUMAN, OF BATTLE CREEK, MICHIGAN.

BOOT-SCRAPER.

1,132,646.

Specification of Letters Patent. Patented Mar. 23, 1915.

Application filed January 30, 1915. Serial No. 5,287.

To all whom it may concern:

Be it known that I, PAUL H. BAUMAN, a citizen of the United States, residing at Battle Creek, Michigan, have invented certain new and useful Improvements in Boot-Scrapers, of which the following is a specification.

This invention relates to improvements in boot scrapers.

10 The main objects of this invention are to provide an improved boot scraper adapted to be produced as an integral stamping which is easily and securely attached, economical to produce, and attractive in appearance.

Further objects, and objects relating to structural details, will definitely appear from the detailed description to follow.

20 I accomplish the objects of my invention by the devices and means described in the following specification.

The invention is clearly defined and pointed out in the claims.

25 A structure which is a preferred embodiment of my invention is clearly illustrated in the accompanying drawing forming a part of this specification, in which:

30 Figure I is a rear perspective view of my improved scraper. Fig. II is a detail vertical section through one of the attaching arms and a support, such as a porch step, having my improved scraper mounted thereon. Fig. III is a plan view showing one step in the manufacture of my improved 35 scraper. Fig. IV is a detail rear perspective view of a slightly modified structure.

In the drawing similar reference numerals refer to similar parts throughout the several views.

40 Referring to the drawing, my improved foot scraper is formed integrally of a metal stamping and comprises a blade 1 having supporting arms 2 at the ends thereof, the arms being provided with horizontal portions 3 adapted to rest upon the top of a support 4 such as a step or the like. The arms 3 are perforated at 5 to receive the attaching screws 6. Lugs 7 are struck downwardly from the supporting arms and 45 adapted to engage the edge of the support, as shown in Fig. III. The ends of these lugs are turned rearwardly to provide brads 8 adapted to be driven into the edge of the support. Owing to the distance between

the arms 2 and the lugs 7, the blade is spaced 55 from the edge of the support so that the scrapings fall between the blade and the porch and do not collect on the rear side of the blade. The lugs 7 coacting with the screws 6 form a very secure attaching means 60 for the scraper and one well adapted to stand the strains to which the scraper is subjected in use.

In the modified construction, shown in Fig. IV, the lugs 9 are perforated at 10 to 65 receive screws. The embodiment shown in Figs. I and II is, however, preferred.

Fig. III illustrates one step in the manufacture of my improved scraper which is the forming of a blank from a piece of metal 70 of suitable weight. The lugs 7 are then struck down and the arms bent along the dotted lines 11. The blade is preferably provided with rounded projections 12 at its ends which prevent the foot from slipping 75 from the blade and also adds to the appearance by providing rounded corners.

Having thus described my invention what I claim as new and desire to secure by Letters Patent is:

1. A scraper formed as an integral stamping comprising a blade portion and supporting arms at the ends thereof, said arms terminating in horizontally disposed attaching portions perforated to receive attaching 85 screws and having lugs struck downwardly therefrom adapted to engage the edge of the support on which the arms rest, the ends of said lugs being turned rearwardly and adapted to be driven into the edge of the 90 support.

2. A scraper comprising a blade portion and integral supporting arms at the ends thereof, said arms terminating in horizontal attaching portions having lugs struck downwardly 95 therefrom and adapted to engage the edge of the support on which the arms are mounted whereby the blade is supported in a spaced relation to the edge of the support.

In witness whereof, I have hereunto set my hand and seal in the presence of two witnesses.

PAUL H. BAUMAN. [L.S.]
